UNITED STATES PATENT OFFICE.

JOHN B. DOYLE, OF LANSINGBURG, ASSIGNOR OF ONE-HALF TO JEROME F. YOUNG, OF NEW YORK, N. Y.

DESIGN FOR A FOOT WARMER OR SUPPORT.

SPECIFICATION forming part of Design No. 18,961, dated March 12, 1889.

Application filed February 8, 1889. Serial No. 209,198. Term of patent 7 years.

To all whom it may concern:

Be it known that I, JOHN B. DOYLE, of Lansingburg, in the county of Rensselaer and State of New York, have invented and produced a new and original Design for a Foot-Warmer or Support, of which the following is a specification, reference being had to the accompanying drawings, forming part thereof.

Figure 1 is a perspective view of my newly-
10 designed foot warmer or support, and Fig. 2
is an end elevation of the same.

The leading feature of my design consists
of a partly-flat and partly-sloping top, the latter
15 terminating in a ledge near the bottom
and in vertical walls, rounded ends, and curved
projections appearing thereon, substantially
as illustrated in the drawings.

A is the top of the foot warmer or support,
showing an incline or slope α , ledge b , and
20 flat top c , the slope α being intermediate to
said ledge and flat top. The back B of the

foot warmer or support is perpendicular and
at right angles to the flat bottom C . Between
the flat bottom C and the top of the
ledge b and bottom C appears a narrow per-
pendicular front wall, d . The ends D of
the warmer are curved or rounded, as shown,
and at the center of each end is formed a
curved lug or projection, f , as shown clearly
in Fig. 1.

I claim—

The design for a foot warmer or support
herein shown and described, the same com-
prising the flat top c , ledge b , intermediate
slope, α , vertical walls B , d , flat bottom C ,
rounded ends D , and curved lugs or projec-
tions f .

JOHN B. DOYLE.
